Primary Examiner—Ruth McInroy**Attorney, Agent, or Firm**—Timmons & Kelly**[57] CLAIM**

The ornamental design for a vacuum cleaner attachment for cleaning ceiling fan blades, as shown and described.

DESCRIPTION

FIG. 1 is a top plan view of a vacuum cleaner attachment for cleaning ceiling fan blades showing my new design;

FIG. 2 is a front elevation thereof, the opposite side being identical;

FIG. 3 is a bottom plan view thereof; and,

FIG. 4 is a right side elevation thereof, the opposite side being identical.

FIG. 1

FIG. 2

FIG. 3

FIG. 4
